UNITED STATES PATENT OFFICE

148,319

DESIGN FOR A CRÈCHE

William Niederhausen and Conrad Dallwin Hamilton, New York, N. Y.

Application July 25, 1946, Serial No. 131,927

Term of patent 3½ years

(Cl. D29—23)

To all whom it may concern:

Be it known that we, William Niederhausen, a citizen of Germany, who has declared his intention of becoming a citizen of the United States, and Conrad Dallwin Hamilton, a citizen of the United States, each residing at New York, in the county of New York and State of New York, have invented a new, original, and ornamental Design for a Crèche, of which the following is a specification, reference being had to the accompanying drawing, forming a part thereof.

Figure 1 is a front elevation of a crèche embodying our design,

Figure 2 is a side elevation thereof,

Figure 3 is a bottom view, and

Figure 4 is a reduced-scale rear view of the crèche shown in Fig. 1.

We claim:

The ornamental design for a crèche, as shown.

WILLIAM NIEDERHAUSEN.

CONRAD DALLWIN HAMILTON.
